FLYER

Charles H. Colvin, Morris Township, Morris County, N. J.

Application November 2, 1935, Serial No. 48,005

6 Claims. (Cl. 117—26.5)

This invention relates to a "flyer" or running guide for use in connection with apparatus for twisting yarn.

As is well known it is desirable when throwing 5 yarn, that is, when twisting yarn by drawing it off a revolving bobbin to impart a twist to the yarn, to interpose a running guide or "flyer" between the supply bobbin or yarn package and the fixed and reciprocating guides which lead the 10 yarn to the receiving or take-up bobbin.

This invention aims at improving the construction of such flyers to make them more suitable and useful for the purpose described.

It is an object of this invention to provide 15 a flyer which may be readily installed on present throwing spindles, and which may be operated at high speed without throwing oil, and for long periods without addition of lubricant to the bearings thereof. It is a further object to 20 provide a flyer wherein the guide wires are clamped and keyed in place and wherein such wires are readily replaceable.

The accompanying drawing illustrates a preferred form of my invention, but it is not intended to limit the scope of the invention to the precise structure disclosed, many modifications being possible within the scope of my invention as hereinafter claimed.

Figure 1 is a view of my flyer in elevation, including by way of illustration a portion of the throwing frame and of the yarn to be thrown.

Figure 2 is a view in section on the line 2—2 of Figure 1, including a fragmentary view of the bobbin or yarn package and of the spindle 35 blade by which it is carried.

Figure 3 is a view in section through the flyer at the line 3—3 of Figure 2, and illustrates particularly the form of the wires and the method of clamping and keying said wires.

Now referring more particularly to the drawing for an explanation of the invention, the spindle blade 8 carries the supply bobbin 9 upon which is wound the yarn 10 to be twisted. A single thread of the yarn is shown at 10' in Figure 1.

Also carried by the blade 8 and illustrated as telescoped over it (though it might equally well be inserted in a socket within the blade) is the body 11 of the flyer. Such blades are commonly 50 made with a cylindrical portion 13 surmounted by a tapered portion 14. I make the body 11 of my flyer recessed on two diameters, the larger of which diameters fits snugly upon the cylindrical portion 13 of the blade, where it is held 55 tight by the spring tension created by slightly

pinching the body to tend to close the slot 16; and the smaller of such diameters forms a step in relation to said larger diameter and at this step rests on the tapered portion 14 of said blade near its extreme top. I thus provide for the 5 association of flyer and blade in such a way that there will be little or no radial play between said flyer and blade, and hence little chance for the flyer to vibrate or to run out of truth. An outer section 17 of the body 11 is 10 knurled to aid in mounting and dismounting the flyer.

At its upper end the body 11 carries a staff 18 upon which is journaled the barrel 19, by means of bearings 21 and 22 which are preferably of a material such as "oilite bronze" which is porous and holds a supply of oil sufficient for operation for a long period without renewal of lubricant. This feature is of importance because the lubrication of flyers involves the hazard 20 of spoiling the yarn by getting oil on it. Such a bearing material as I propose to use largely eliminates this difficulty because the porous bronze tends to retain the oil rather than to let it fly out as does an ordinary bearing. 25

The barrel 19 is retained on the staff 18 by a slotted nut 20. The outside of the barrel 19 is substantially cylindrical, with an enlarged upper end which may be hexagonal as shown or otherwise arranged for easy gripping by tool or by 30 hand, and the lower end carries a thread upon which is screwed a nut 23. Interposed between the extended head and the nut 23 are a washer 24, two guide wires 26 and 27 and sleeve 28.

In use the yarn 10' is led from the bobbin 9 35 through one of the eyes of guide wire 26, through one of the eyes of guide wire 27, through the fixed guide eye 29 attached to a part of the frame 31 and thence through the reciprocating guide (not shown) to the receiving bobbin (not shown). 40

It will be noted from Figures 2 and 3 that the sleeve 28 is recessed at each end, and that the walls of each of these recesses are cut away as at 32 and 33 in Figure 3. The wires 26 and 27 are made with their center portions of the simple 45 substantially semi-circular form shown in Figure 3, adapting them to be laid in the recesses of the sleeve 28 and to be clamped in place by screwing up of the nut 23 on barrel 19. The maintenance 50 of the interrelationship of the axes of the wires 26 and 27 about the axis of the staff 18 is provided by the notches 32 and 33, and by corresponding notches at the lower end of the sleeve 28, through which pass the extending portions 55 of the wires 26 and 27.

Having thus disclosed and described my invention, I claim its novelty as follows:

- 5 1. In combination with a frame for throwing yarn and having a spindle, a flyer, said flyer comprising a body having a socket adapted to fit over and rest upon the top of said spindle and a staff, a guide for said yarn, and said guide journaled upon said staff.
- 10 2. In a flyer, means for clamping guide wires, comprising a substantially cylindrical member having an enlarged head on one end and having the other end threaded, a nut on said threaded end, and a sleeve having at each end an annular recess, the walls of which are cut away at opposite sides, guide wires positioned in said recesses and extending through said cut-away walls and adapted to be locked in place by tightening the aforesaid nut.
- 15 3. A flyer for the blade of a throwing spindle said blade having a cylindrical portion surrounded by a tapered portion, comprising a body having a staff, a yarn guide journaled upon said staff, said body being recessed on two diameters, the larger diameter adapted to fit upon said cylindrical portion of said blade and having a slot throughout a part of the length of said larger
- 20 diameter to cause the lower end of said body to fit snugly upon said blade, and the smaller diameter adapted to fit upon said tapered upper portion of said blade.
- 25 4. A flyer for the blade of a throwing spindle said blade having a cylindrical portion, comprising a body having a staff, a yarn guide journaled upon said staff, said body being recessed and adapted to fit upon said cylindrical portion of said blade and having a slot throughout a part of the length of said body to cause the end of said body to fit snugly upon said blade.
- 5 5. In a flyer for a throwing spindle, a body having a socket adapted to fit over and rest upon the top of said spindle and a staff, a guide-carrying member, porous bearing elements interposed between said member and said staff to journal said member on said staff, and said porous elements being impregnated with a lubricant.
- 10 6. In a flyer for a throwing spindle, a body having a socket adapted to fit over and rest upon the top of said spindle and a staff, a guide-carrying member, and porous bearing elements interposed between said member and said staff to journal said member on said staff.
